UNITED STATES PATENT OFFICE.

FRANK K. BERRY, OF BATTLE CREEK, MICHIGAN, ASSIGNOR TO A.-B. STOVE COMPANY, OF BATTLE CREEK, MICHIGAN, A CORPORATION OF MICHIGAN.

PROPORTIONAL GAS AND AIR MIXER.

1,159,737.

Specification of Letters Patent.

Patented Nov. 9, 1915.

Application filed June 12, 1915. Serial No. 33,819.

To all whom it may concern:

Be it known that I, FRANK K. BERRY, a citizen of the United States of America, residing at Battle Creek, in the county of Calhoun and State of Michigan, have invented certain new and useful Improvements in Proportional Gas and Air Mixers, of which the following is a specification, reference being had therein to the accompanying drawings.

The invention relates to valves for controlling gas and air in burners of the Bunsen type, being more particularly adapted for use upon gas ranges.

In the present state of the art in gas stove construction it is usual to mix the gas and air in a tube leading to the burner, the gas being injected centrally in the end of said tube, and the air being controlled by a rotary register or damper. It is also usual to have the burner and mixing tube freely detachable from the valve so as to permit of cleaning.

It is the object of the present invention to obtain a construction of valve which controls both the gas and air supply, also the size of the orifice in the nozzle through which the gas is injected, the whole constituting a unit mountable upon the gas supply conduit independent of the detachable burner and mixing tube.

In the drawings: Figure 1 is a perspective view of the unit; Fig. 2 is a front elevation thereof showing a different position of adjustment; Fig. 3 is a horizontal section showing the unit in connection with the mixing tube indicated in dotted lines; and Fig. 4 is a view similar to Fig. 3, showing a different adjustment of the valve and nozzle.

For the proper combustion of gas it is necessary to maintain a standard proportion of gas and air without regard to the volume. It is equally important to effect a thorough commingling of the gas and air before combustion takes place, and this is usually accomplished by a Bunsen burner, where a fine jet of gas is directed into a larger tube for commingling with the air. The mixture is affected by the velocity of the gas jet, and this in turn is altered by adjustment of the valve. It is therefore difficult to maintain uniform conditions in quality of the mixture with varying quantities, so that an adjustment which is proper for a full head of gas

will not be suitable where the burner is turned down. With my improved construction this defect is avoided by a simultaneous and corresponding adjustment of the gas valve, the air supply and the diameter of the orifice for the gas jet, so that under all conditions the proper proportion of gas and air is maintained.

In detail, A is the casing of the gas valve, and B is the valve preferably of the tapering plug type.

C is the nozzle forming the delivery end of the casing A, and arranged to project into the mouth of the mixing tube D, shown in dotted lines in Fig. 3. Mounted upon this nozzle C is a cap member E for engaging the bell-shaped mouth of the mixing tube, said cap being apertured at F for the admission of air.

G is a rotary register slide or damper mounted upon the nozzle C adjacent to the cap E and adapted in different positions of adjustment to vary the open area of the apertures F.

H is a finger projecting from the stem of the valve B, and slidably engaging a bearing on the damper G, preferably formed by a pair of ears I and I' projecting therefrom. The end of the finger H has a spherical portion H' fitting between said ears, and the latter are so fashioned that in the rocking movement of the valve a corresponding oscillation of the member G is effected. Thus, in the position of the valve in which the port J is wide open the finger H will be in the position shown in Fig. 2, and the register G will be held in a position for fully opening the ports F. On the other hand when the valve is turned toward its closed position, as indicated in Fig. 4, the register G will be rocked toward the position shown in Fig. 1, where the area of the openings F is restricted. It is evident that by properly proportioning the parts the same ratio between the volume of gas and air may be maintained in all positions of adjustment.

For delivering the full head of gas when the valve B is open, an aperture of predetermined area in the end of the nozzle is necessary, but where the valve is nearly closed this aperture will be too great to maintain the proper velocity in the discharged stream of gas. I have therefore provided means for adjusting the area of the discharge nozzle, which is automatically operated by the movement

- of the valve. As shown, K is a conical bushing having a threaded engagement with the end of the nozzle and having an aperture K' for the maximum discharge of gas.
- 5 L is a split tube within the nozzle having tapering resilient jaws L' which fit within the conical bushing. The shank of this tube extends into contact with the valve plug, and the latter is provided with a cammed portion
- 10 M which permits the restriction and opening of the jaws when the valve port is full open, and the forcing of the jaws outward into the conical bushing to close the same as the valve is turned toward its closest position.
- 15 This produces the enlargement and contraction of the gas orifice corresponding to the port opening of the valve, thereby maintaining a substantially uniform velocity in the discharged stream of gas.
- 20 With the construction as described, when mounted upon a stove the mixing tube D of the burner will extend into engagement with the flange E' of the cap member E without the necessity of any permanent attachment.
- 25 This permits of removing the burner whenever it is necessary to clean the same, and replacing without disturbing the valve or the coöperating parts operated thereby.
- What I claim as my invention is:—
- 30 1. The combination with a gas valve casing having a projecting nozzle, of a collapsible sleeve within said nozzle for varying the discharge opening thereof, an air register valve mounted upon said nozzle, a plug valve within said casing cammed to operate said collapsible sleeve in the opening and closing of the valve, and a finger projecting from said plug valve operatively engaging said air register valve to effect a corresponding movement thereof. 35
2. The combination with the casing of a gas valve having a projecting discharge nozzle, of a bell-mouthed mixing tube into which said nozzle projects, a cap for the mixing tube flanged to detachably engage the same and mounted upon said nozzle, said cap being formed with an air inlet, a closure for said inlet rotatably mounted upon the nozzle, and a connection between the gas valve and said closure for compelling a proportionate movement. 40
3. The combination with a gas valve and its casing, the latter having a projecting nozzle, of a conical bushing engaged within the end of the nozzle, and a collapsible sleeve within the nozzle, extending into said conical bushing, the valve having a cammed portion whereby the sleeve is longitudinally actuated by rotation of the valve, varying the nozzle opening proportionately to the variation in the gas valve opening through the insertion of the nozzle in the conical bushing or its withdrawal therefrom. 45
- 50
- 55
- 60
- In testimony whereof I affix my signature.

FRANK K. BERRY.
